UNITED STATES PATENT OFFICE.

LEWIS MOORE, OF JOLIET, ILLINOIS.

DESIGN FOR A COMBINED STOVE DOOR AND FRAME.

Application filed October 26, 1923. Serial No. 7,599. Term of patent 14 years.

To all whom it may concern:

Be it known that I, LEWIS MOORE, a citizen of the United States, residing at Joliet, Illinois, in the county of Will, have invented a new, original, and ornamental Design for Combined Stove Door and Frame, of which the following is a specification, reference being had to the accompanying drawing, forming a part thereof.

The figure on the drawing is a perspective of a combined stove door and frame, embodying my invention.

I claim:

The ornamental design for a combined stove door and frame, as shown.

LEWIS MOORE.
